UNITED STATES PATENT OFFICE.

ARMINI GENDRON AND JOHN R. RICHARDSON, OF MADERA, CALIFORNIA.

MOLD FOR CONSTRUCTING CONCRETE WALLS.

1,240,435.

Specification of Letters Patent. Patented Sept. 18, 1917.

Application filed December 11, 1915. Serial No. 66,322.

To all whom it may concern:

Be it known that we, ARMINI GENDRON and JOHN R. RICHARDSON, both citizens of the United States, residing at Madera, in 5 the county of Madera and State of California, have invented certain new and useful Improvements in Molds for Constructing Concrete Walls, of which the following is a specification.

10 This invention relates to improvements in wall molds which are used in building hollow walls from concrete or similar material, the object of the invention being to provide means for constructing hollow walls from 15 concrete such walls having internal projecting portions or abutments which are located opposite one another, the inner and outer walls being tied together.

Another object of our invention is to provide the outer molds with means for recessing the walls to provide means for holding the molds in position in casting the next 20 course of the wall and to provide the inner wall with recesses which may be used to 25 receive joist-hangers.

A further object of our invention is to provide a mold of such construction that the same may be used in molding hollow walls of concrete, the parts of the mold being 30 interchangeable and of such a size that the units may be handled without the use of scaffolding.

In the accompanying drawings which illustrate a preferred form of our invention, 35 Figure 1, is a side elevation. Fig. 2, is a plan view showing the parts of the mold set up to receive the concrete. Fig. 3, is a transverse sectional view, taken substantially on the line 3—3 of Fig. 2. Fig. 4, 40 is a horizontal section of a portion of the hollow wall and of a part of one of the outer molds. Fig. 5 is a detail perspective view. Fig. 6, is a vertical sectional view of a portion of one of the inner molds, and 45 Figs. 7, 8 and 9 are detail views.

In pouring or constructing hollow walls from a concrete mixture we provide exterior mold plates or forms 10 and 10', the upper edges thereof having properly spaced 50 loops 11 and 11' to receive the end portions of spacing bars. The exterior or outer mold plates or forms 10 and 10' have formed

therethrough elongated slots 12 and 12' which are both longitudinally and vertically disposed, the lower slots being positioned nearer the lower edges of the side pieces than the distance between the upper slots and the upper edges of the side pieces, the purpose of such arrangement being to position the molds or forms so that they 55 may be maintained by the walls as the construction of the same progresses. The exterior faces of the mold plates or forms 10 and 10' have attached thereto battens 14, the ends of the battens terminating on a 60 line with the slots 12 and 12', and to the ends of the battens are pivoted members or flat bars 13, the projecting ends thereof being adapted to be positioned to extend through the slots 12 and 12' to form in the 65 concrete recesses, which primarily serve to sustain the side plates in proper position in molding the walls and secondly to provide in the walls recesses which are adapted to receive hangers for the beams of the building, or other hangers used for carrying a 70 scaffold used in dressing the outer walls and in pointing up the same. The recesses may be utilized to receive blocks of wood or wedges to which strips may be nailed. The 75 indenting members or bars 13 have projecting portions 13' that provide grasping portions for moving said members upon the pivots that enter the ends of the battens 14.

The mold plates or forms 10 and 10' have 80 attached thereto at suitable intervals vertical strips 15 to provide hard surfaces against which cams 16 on U-frames 17 will abut, such frames providing means for clamping the inner and adjustable forms 18 85 to the outer mold plates.

The U-frames 17 on one side have pivoted thereto cams 16, which are integral with arms which have bent over portions that contact with the outside edge of the part of the frame to which the cams are secured. The opposite member of the frame 17 from the member having the cams is adapted to contact with inner forms to draw when the cams are operated, the side pieces of 90 the inner forms toward the side pieces of the outer form, and in use the U-frames will be positioned so that the cams will impinge against the strips 15. In practice the U- 95

frames 17 are placed in position for use adjacent to the transverse spacing bars the ends of which are passed through the loops 11 and 11' and the inner end of the U-
5 frame may depend below the bottom edge of the inner core, and the cams 16 are positioned so that indenting members 13 will be below the cams. The inner arm of the U-
10 frames will bear against the sides of the inner forms and when the arms of said frames are of equal length the arm without the cams may depend below the sides of the inner forms.

The inner forms 18, consist of side pieces 15 19 and 19' which have secured thereto strips or battens 20 and 20', the strips or battens being connected to a central bar 21 by means of toggle-links 22 that are adapted to be flexed upward when the bars are 20 raised, said bars 21 being connected by a strip 23 that is attached to their lower ends. The side pieces 19 and 19' of the forms 18 are provided with turn-pins 24 which project upward from the upper edges of said 25 side pieces adjacent to their centers, the turn pins being for engagement with spacing bars 25 the ends of which are overlaid by the loops 11 and 11' which extend upward from the exterior side plates of the 30 mold.

The spacing or transverse bars 25 are provided with upward extending and centrally located loops 26, and with longitudinal slots 27 for the passage therethrough of the turn-pins 24 on the side pieces of the inner form. The centrally located loop of the spacing bar, the loops 11 and 11', and the turn pins 24 connect the inner and outer forms so that they may be raised in unison when 40 power in an upward direction is applied to the loops 26.

The inner molds or forms 18, are spaced apart one from the other and the spaces are spanned by sheet metal lap plates or members 29, which are somewhat longer than the height of the inner forms 18. The parts 29 are bent or shaped to provide alined sides 30 which will overlie the end portions of the side pieces of the inner forms, and other 45 bends shape the lap plate or member 29 to provide inward extending and converging portions 31 which are connected by a central portion 32 that is provided at its lower end with a recess 33 to provide a space which 50 will overlie tie-bars. The sheet metal members 29 are located opposite and when used will form inward extending and oppositely located abutments which are integral with the walls, and in molding a hollow wall the 55 cement or concrete is poured about rods 34, the rods in the abutments of the wall being connected by suitable ties 35.

The ends of the mold or form may be closed when desired in any appropriate 60 manner as for instance by an end piece 36

that is provided on one side with battens or strips 37 and 38 for engagement with the ends 30 of the members 29 and the ends of the sides 10 and 10' of the outer forms, as shown by Fig. 2 of the drawings.

In constructing a hollow concrete or cement wall, the foundation is first molded and for this purpose the sides 10 and 10' and the spacing bars are used, vertical bars or rods 34 being in place are embedded in the concrete, and when the concrete has partially set the upper indenting bars are forced into the concrete to form recesses therein. When the foundation has set tie-bars 35 are placed in position to engage with opposite vertical rods 34, the side pieces 10 and 10' of the mold are raised and are placed so that the ends of the lower indenting members 13, will enter the recesses previously formed in the concrete and when thus positioned a considerable portion of the outer mold plates or forms will overlie the sides of the previously molded foundation or wall. The inner cores or forms are placed in position so that the turn-pins 24 will be in line with the loops 11 and 11', the spacing bar 25 is passed under the loops and the turn-pins 24 are passed through the slots 27, the blocks 28 being between the inner and outer forms. The sheet metal lap plates or 95 members 29 which span the spaces between the inner forms and form abutments which extend inward from the walls being placed in position are held by the inner forms, the recesses in the lower edges overlying tie-bars 35 that engage with the rods 34. The spacing bars have their ends passed through the loops 11 and 11' of the outer forms, and when the inner forms are expanded by depressing the center bars 21, the turn pins 100 24 will be moved in the slots through which they pass, and the inner and outer forms will be properly spaced by the blocks 28 on the underside of the bars 25. The forms may be drawn toward each other by U- 105 frames 17 that are provided with cams, and in practice end pieces may be provided to close the ends of the forms.

Either solid or hollow walls may be built with the forms hereinbefore described, and such hollow walls will have inwardly extending and oppositely located abutments which are connected by tie-bars.

The mold hereinbefore described may be used in the casting or pouring of concrete 120 walls with air spaces between the two side walls, and with our molds or forms one of the walls may vary in thickness from the other wall, by properly setting the inner members of the mold, and when the walls 125 between the abutments are of a different thickness from the opposite walls abutments of the same size may extend upward for the entire height of the wall, the lap plates which form truncated wedge shaped abut- 130

ments are of greater rigidity than if curved and the abutments will have a greater surface exposed to the air which results in the more quickly setting of the cement mixture.

5. We do not limit ourselves to the precise construction of the parts herein shown and described, as the parts may be modified within the scope of our claims.

We claim.

10. 1. In combination with means for supporting the outer forms of molds used in the construction of concrete walls, of outer forms provided with apertures therethrough which are positioned in both vertical and 75 longitudinal alinement, and wall-indenting and form-supporting means which are pivotally associated with the forms.

2. In a mold for use in constructing walls from concrete, outer form plates having vertically and horizontally alined apertures therethrough, means pivotally associated with the plates and provided with end members which extend through the apertures to form recesses in the concrete when positioned to extend beyond the inner faces of the form plates.

3. In a mold for constructing walls from concrete and the like, outer side plates having apertures therethrough, said apertures being in vertical alinement and spaced at different distances from the top and bottom edges of the side plates, and wall-recessing and mold supporting means which are pivotally attached to the outer side plates.

35. 4. In a mold for use in the construction of walls from concrete, side plates having vertically and horizontally alined apertures therethrough the apertures being spaced to one side of the longitudinal center of the 100 side plates, wall-indenting and side plate supporting members maintained in pivotal engagement with the side plates, said wall indenting and side plate supporting members having horizontally disposed end members of a length sufficient to extend beyond the inner face of the side plates.

5. In a mold for use in the construction of walls from concrete, side plates having vertically and horizontally alined apertures 105 therethrough, means pivotally associated with the side plates and adapted to be swung into position for forming recesses in the wall and similar means for engagement with the recesses to space and support the side 110 plate previous to molding a further portion of the wall.

6. In a mold for use in the construction of hollow concrete walls, the combination with inner forms substantially as shown, of outer forms which are of a greater height 115 than the inner forms, means for associating the forms to maintain the upper ends thereof on the same plane, apertures which are elongated horizontally through the outer forms, mold supporting and spacing means

pivoted to the outer face of the outer mold forms and provided with flat inner ends of a length sufficient to extend beyond the inner face of the outer forms, for the purpose set forth.

7. In molds for use in the construction of hollow walls from concrete, outer forms, expandable inner forms of less length and depth than the outer forms, and angularly bent members located between the ends of 75 the inner forms and engaging therewith, said members being shaped to provide the walls with oppositely located and inwardly extending abutments.

8. In molds for use in the construction of hollow walls from concrete, outer forms provided with loops which extend above the upper edges of the forms, inner forms provided with turn-pins which extend above the upper edges of the inner forms, a spacing 85 bar provided with slots for the passage therethrough of the turn-pins; said spacing bar being of a length to engage with the loops attached to the outer molds.

9. In combination with outer forms provided with upward extending loops, of expandable inner forms provided with upward extending turn-pins, and a spacing bar having therethrough longitudinal slots for the passage of the turn-pins and means for engagement with the inner faces of the inner forms and the outer faces of the outer forms.

10. In a mold for use in constructing hollow walls from concrete, the combination of outer forms, inner forms of less length than the length of the outer forms and provided with recesses, abutment forming members constructed to be maintained in place by engagement with the recesses in the sides of the end portions of the inner forms and provided with angular bends to provide ends, converging sides and a flat central portion.

11. In a mold for use in constructing hollow walls from concrete, comprising inner and outer forms, the inner forms being separated longitudinally, lap plates having a plurality of bends which shape the plate and provide the same with converging sides that are connected by a flat portion and alined end portions for engagement with the inner 115 forms.

12. In a mold the combination with inner and outer forms the inner forms being of less length than the length of the outer forms, lap plates that are adapted to bridge 120 spaces between the ends of the inner forms to provide on the opposite inner walls abutments of a truncated wedge shaped configuration which are connected by tie bars and recesses in the lap plates that are adapted to receive the tie bars.

13. In a mold for use in the construction of hollow walls which are molded *in situ* each of the walls having oppositely located and inward extending abutments with con- 130

verging sides, the walls being tied together by ties which span the space between the abutments, the combination of outer forms, inner forms of less length than the outer forms, abutment forming members having inward converging side walls and end portions for engagement with the inner sides of

the inner forms the lower edges of the abutment forming members having formed therein recesses for the reception of tie bars, substantially as shown.

ARMINI GENDRON.
JOHN R. RICHARDSON.
